BED SPRING

Filed Feb. 26, 1925

Inventor
Charles H. Gail
by W. H. Maxwell
his Attorney

UNITED STATES PATENT OFFICE.

CHARLES H. GAIL, OF LOS ANGELES, CALIFORNIA, ASSIGNOR TO LOS ANGELES SPRING BED COMPANY, OF LOS ANGELES, CALIFORNIA, A CORPORATION OF OHIO.

BED SPRING.

Application filed February 26, 1925. Serial No. 11,734.

This invention relates to a spring such, for instance, as a bed spring and it is a particular object of the invention to provide an improved spring in which the parts are effectively braced and also held against lateral movement.

Spring structures, such as are used in beds, and the like, usually comprise a heavy base frame and a light top frame supported on the base frame by a plurality of helical springs. The object of making the top frame comparatively light and of supporting it in manner just described, is to make it comfortable and to give it the desired resiliency in a vertical direction. In obtaining these qualities with the usual construction the top frame is more or less flexible and is more or less freely movable a substantial amount laterally or in a horizontal direction with reference to the base frame. The flexibility of the top frame and the lateral or horizontal movement of the top frame is objectionable and various devices have been provided to overcome it.

This invention has particular reference to a construction or device for bracing or stiffening the top frame and overcoming the undesirable horizontal or lateral shifting movement of the top frame with relation to the base frame.

A further object of the invention has been to provide means for yieldingly bracing the top frame of a spring against horizontal movement.

A particular object of this invention has been to provide a practical effective means other than the usual helical springs for bracing or supporting the top frame.

Another object of this invention has been to provide a brace of the character mentioned which is extremely simple both in construction and operation and which involves very few simple and inexpensive parts.

The objects and features of my invention will be best and more fully understood from consideration of the following detailed description of a typical form and application of the invention throughout which description reference is made to the accompanying drawings in which

Fig. 1 is a plan view of a portion of a bed spring showing a brace embodying the present invention applied thereto.

Fig. 2 is a transverse sectional view taken as indicated by line 2—2 on Fig. 1.

Fig. 3 is a plan view taken as indicated by line 3—3 on Fig. 2 and

Fig. 4 is an enlarged detailed sectional view taken as indicated by line 4—4 on Fig. 3.

I have, in the drawings, illustrated a typical form of bed spring construction comprising a base frame 10, a top frame 11, and a plurality of helical springs 12 supporting the top frame on the base frame. The base frame, in accordance with usual practice, is a rectangular frame comprising side parts 14, end parts (not shown) and a plurality of intermediate parts 15. The side and end parts of the frame are usually comparatively heavy so that they form a rigid strong frame, the intermediate parts 15 being arranged in spaced relation within the frame, to carry the springs 12. In accordance with the usual practice the intermediate frame parts 15 extend transversely of the frame between the side parts 14 as I have illustrated in the drawings. The intermediate frame parts 15 are in the form of flat straps or strips of material arranged vertically and spaced and related so that they extend directly under the springs 12 to effectively support them. The springs 12 may be the usual form of helical springs employed in structures of this kind and may be connected to the various parts of the base frame by means of tie wires 17. The upper ends of the springs 12 are connected together by crossed helical springs 20 and are connected with the top frame 11 by tie wires 21.

The top frame 11 is usually a substantially rectangular frame somewhat lighter in construction than the base frame 10. The top frame is usually formed of heavy wire and comprises side parts 25 and end parts (not shown). The construction thus far described may be considered a typical bed spring construction, it being understood, of course, that bed springs vary considerably in the exact design and proportioning of the frames, the arrangement and manner of connecting the helical springs to the frames and with each other, etc.

The present invention is concerned primarily with improved means for bracing or reinforcing the top frame 11 and, for bracing the frames against relative movement laterally, particularly for bracing the top frame against lateral or horizontal movement with reference to the base frame. When I use the

term lateral movement I mean to include not only movement sidewise, but also endwise, that is, the present invention may be employed to hold the top frame against movement sidewise or endwise, or both. The bracing means provided by my invention includes a brace member 30 connected with the top frame 11 and with the base frame 10. The brace member has a straight horizontal or lower part 31 arranged between two spaced parts of the base frame, for instance, between two adjacent intermediate frame parts 15. The lower part 31 of the brace is comparatively long as illustrated in the drawings and is connected, preferably at its ends to the frame parts 15 by tension springs 33. The tension springs 33 are preferably helical springs disposed transversely of the part 31 between the part 31 and the frame parts 15. In the preferred form of construction the lower part 31 of the brace is connected with the frame parts 15 only at its ends however, it will be apparent that any desired number of connections may be made between the part 31 and the frame part 15. In addition to the lower part 31 the brace includes a part 35 which extends upwardly from the part 31 to connect with the top frame 11. The part 35 preferably extends diagonally upwardly from one end of the lower part 31 and is arranged so that its upper end connects directly with the top frame 11, for instance, with one of the side parts 25 of the top frame. In the particular form of the invention illustrated in the drawings, the brace 30 is formed of sheet metal bent into a channel shape, the upper end of the diagonally disposed part 35 being flared out and bent around the frame part 25. This manner of connecting the brace with the top frame is particularly simple, effective and is desirable as it permits of some movement between the frame and brace. When the brace is formed in the manner just described, it may be provided at suitable points with openings to receive loops 40 provided on the ends of the springs 33. When it is desired to brace the side parts of the top frame or to brace the top frame against side movement the spring may be equipped with one or more braces 30 arranged transversely of the spring and connected with the side part or parts of the top frame 11. It is to be understood that one or more braces may be provided at a side of the spring and that braces may be provided at either or both sides of the spring as circumstances may require. Further, if it is desired to brace an end part of the frame or to brace the top frame against endwise movement one or more braces 31 may be provided longitudinally of the spring and may be connected with the end part or parts of the top frame. In operation the brace provided by my invention operates to reinforce or stiffen the top frame to hold it in shape and to resist vertical

movement of the edge portion of the top frame to a degree which is desirable. The brace also operates to yieldingly resist or prevent lateral movement of the top frame. When the edged portion of the top frame is moved vertically the springs 33 are flexed in a vertical direction and when it is moved horizontally the springs 33 are flexed in a horizontal direction. When the frame is moved to flex the springs vertically the horizontal part 31 of the brace swings or pivots so that the springs 33 at one end are flexed upwardly and those at the other end downwardly. Movement of the top frame horizontally causes the horizontal part 31 of the brace to move in a substantially horizontal direction which movement is directly resisted by all of the springs 33. By providing the brace with the proper number of springs 33 and with springs 33 of the proper strength the top frame 11 will be braced in the desired manner and will have the desired resistance to lateral movement.

From the foregoing description it will be apparent that the brace provided by this invention is extremely simple in construction and operation, and that it is particularly effective in operation. Further, it is to be noted that the brace is such that it can be applied to practically any usual form of bed spring and does not in any way interfere with the comfort of the spring.

Having described only a typical preferred form of my invention I do not wish to limit myself to the specific details hereinabove set forth, but wish to reserve to myself any changes or variations that may appear to those skilled in the art or fall within the scope of the following claims.

Having described my invention, I claim:

1. A bed spring including, a base frame, a top frame, spring means supporting the top frame on the base frame, a brace connected to one frame and extending diagonally to the other frame, the brace having a portion located substantially in the plane of the said other frame, and a plurality of springs connecting the brace with the said other frame, the springs being connected to the said portion of the brace at points spaced longitudinally thereof.

2. A bed spring including a base frame, a top frame, spring means supporting the top frame on the base frame, a brace connected to one frame and extending diagonally to the other frame, the brace having a portion located substantially in the plane of the said other frame, and springs connecting the brace with said other frame, the springs being arranged substantially in the plane of said other frame and disposed transversely of the brace and being connected to said portion of the brace at points spaced longitudinally thereof.

3. A bed spring including a base frame, a

- top frame, spring means supporting the top frame on the base frame, a brace connected to one frame and extending diagonally to the other frame, the brace having a portion located substantially in the plane of the said other frame, and two pairs of opposing springs connecting the brace with said other frame, the pairs of springs being connected to the said portion of the brace at points spaced longitudinally thereof.
4. A bed spring including a base frame having spaced frame parts, a top frame, a spring means supporting the top frame on the base frame, a brace connected to the top frame and extending diagonally to a position between spaced parts of the base frame, and having a portion extending therefrom in plane of the base frame, and a plurality of springs extending laterally in both directions from the said portion of the brace to said parts of the base frame connecting the brace with the base frame, there being springs engaging said portion of the brace at points spaced longitudinally thereof.
5. A bed spring including a base frame having spaced frame parts, a top frame, a spring means supporting the top frame on the base frame, a brace connected to the top frame and extending diagonally to a position between spaced parts of the base frame, the brace having a part extending parallel to the said base frame parts, and two pairs of coil springs supporting the said part of the brace between said parts of the base frame, the pairs of springs being connected to opposite end portions of said part of the brace.
- In witness that I claim the foregoing I have hereunto subscribed my name this 10th day of December, 1924.
- CHARLES H. GAIL.
